FEEDING MECHANISM FOR ROCK DRILLS

John C. Curtis, Garfield Heights, Ohio, assignor
to The Cleveland Rock Drill Company, Cleve-
land, Ohio, a corporation of Ohio

Application August 12, 1935, Serial No. 35,717

30 Claims.

(Cl. 121—9)

This invention relates broadly to rock drills, but more particularly to feeding mechanism for rock drills of the percussive type wherein the drill is slidably mounted on a suitable support or shell, and is automatically fed toward or away from the work.

One object of this invention is to provide a rock drill with a new and efficient feeding mechanism capable of feeding the rock drill toward or away from the work.

Another object of this invention is to produce a feeding mechanism for a rock drill wherein the latter is capable of relatively long feed toward or away from the work, without increasing the overall length of the assembly.

Another object of this invention is to utilize the force of the jars imparted to the rock drill due to the reversal of the piston strokes therein, for feeding the drill in either direction.

Other objects and advantages more or less ancillary to the foregoing and the manner in which the various objects are attained, reside in the specific construction and aggroupment of the elements peculiar to this structure, as will be come apparent from a more complete examination of this specification, in the claims of which there are assembled certain specific combinations of parts and specific constructions indicative of the scope and spirit of the invention.

In the drawings which illustrate a preferred form of the invention:

Fig. 1 is a side elevational view of a rock drill having the invention applied thereto, the support being shown in section to illustrate details of construction.

Fig. 2 is an enlarged cross sectional view taken through a plane indicated by line 2—2 in Fig. 1, the operative parts of the mechanism being shown in position for feeding motion of the rock drill away from the work.

Fig. 3 is a cross sectional view taken through a plane indicated by line 3—3 in Fig. 2, the operative parts of the mechanism being shown in position for feeding motion of the rock drill 45 toward the work.

Fig. 4 is a view showing the valve mechanism illustrated in Fig. 3, the valve being positioned at the other end of its stroke.

Fig. 5 is a cross sectional view taken through a plane indicated by line 5—5 in Fig. 3.

Fig. 6 is a cross sectional view taken through a plane indicated by line 6—6 in Fig. 3.

Fig. 7 is a cross sectional view taken through a plane indicated by line 7—7 in Fig. 3.

Fig. 8 is also a cross sectional view taken

through a plane indicated by line 8—8 in Fig. 2.

Fig. 9 is an enlarged top plan view of the left end portion of the mechanism shown in Fig. 1.

Referring to the drawings, 15 indicates a fluid actuated rock drill or drilling motor of the percussive type, which is slidably mounted within guideways 16 formed in the upper end of the side walls of a shell 17. Rotatably mounted within the usual back head 18 of the drilling motor 15, there is a throttle valve 19 formed with a central bore 20. This bore is capable of communication with an inlet chamber through a throttle port 21 or 22, and back head port 23. The back head 18 has also incorporated therein a valve mechanism comprising a valve casing 24 formed with a cylindrical bore 25 extending therethrough, and enlarged at one end to form a counterbore 26. Provided within the back head 18 around the valve casing 24, there is an annular groove 27, which opens into the bottom of the counterbore 26 through a port 28. Between its ends, the bore 25 is provided with an internal annular groove 29 in constant communication with a port 30. Leading from the extreme end of the bore 25, there is a port 31 leading to the atmosphere through a port 32. Slidably mounted within the bore 25 in fluid tight engagement with the inner wall thereof, there is a valve 33 terminated at one end by a restricted stem 34. The other end of the valve is provided with a flange 35 slidably mounted within the counterbore 26, and a small annular step 36, the purpose of which will be explained later. Through the flange 35, there is a plurality of small ports 37. The counterbore 26 of the valve casing 24 is normally closed by the front face of a housing 38 secured in abutment with the back head 18 by the usual side bolts 39. This housing has a port 40 leading from the central portion of the counterbore 26. This last port is in communication with the port 30, 40 through a passage 41.

The housing is provided with an enlarged counterbore 42 disposed vertically with respect to the drilling motor 15. Mounted within the counterbore 42, there are two identical rings 43 and 44, the latter located on top of the former. The inner wall of each ring is formed with ratchet teeth 45, while the external wall thereof is shaped to constitute worm gear teeth 46. Rotatably mounted within the two rings 43 and 44, 50 there is an element 47 of a height substantially equal to the combined height of the two rings. This element carries two sets of four pawls 48 and 49. The pawls 48 are located for engagement with the ratchet teeth 45 of the ring 43, 55

and are constantly urged into engagement therewith by spring pressed plungers 50 also carried by the element 47. The pawls 49 located on top of the pawls 48 are capable of engagement with the ratchet teeth 45 of the ring 44, and are also constantly urged into engagement therewith by spring pressed plungers 51. The element 47 is provided with a centrally disposed vertical splined bore 52, adapted to slidably receive a correspondingly splined shaft 53. From the element 47, the shaft 53 extends through the lower portion of the housing 38, where it is laterally guided within a bushing 54. The lower end of the shaft 53 depending from the housing 38 is enlarged and machined to form a pinion 55. The upper end portion of the shaft 53 is threaded to receive a relatively wide washer 56, which is slidably mounted within a cap 57 secured to the housing 38 by bolts 58. The washer 56 is provided with a circumferentially disposed groove 59 having a segment 60 loosely mounted therein. Rotatably mounted within the cap 57 on an axis parallel to the longitudinal center axis of the drilling motor 15, there is a cylindrical member 61 having a handle 62 secured to one end thereof. The member 61 has the other end portion thereof machined eccentrically to form a finger 63, which is rotatably mounted within a radial bore formed through the segment 60. The circumferential wall of the member 61 is provided with a plurality of carefully spaced V-shaped grooves 64, adapted to receive the correspondingly shaped end of a spring pressed plunger 65. The washer 56 is engageable with a brake lining washer 66, secured to the bottom of the cap 57 by rivets 67.

In operative engagement with the worm gear teeth 46 of the ring 44, there are the teeth of a cylindrical rack 68 which is reciprocably mounted within a bore 69 formed within the housing 38. This rack is provided at one end with an enlarged cylindrical head 70, which is reciprocably mounted within a chamber 71 located in coaxial alignment with the bore 69. The cylindrical rack 68 and head 70 are integrally secured to each other to form a power actuated member or piston imparting rotation to the ring 44 in the manner hereinafter described. The chamber 71 is closed by a plug 72, which has a small step 73 extending therefrom into the chamber 71, assuring thereby a space between the plug and the head 70 of the rack 68. The port 40 opening into the valve casing counterbore 26, leads therefrom into the chamber 71 adjacent the plug 72. Intermediate the ends of the chamber 71, there is a small vent 74 which leads to the atmosphere. The cylindrical rack 68 is constantly urged toward the plug 72 by a compression spring 75, which has one end seated on the bottom of the bore 69, while the other end thereof is engaging the bottom of a bore 76 formed within rack 68.

Engaging the worm gear teeth 46 of the ring 43, there are the teeth of a relatively short cylindrical rack 77 located within a flat bottom bore 78 provided within the housing 38. The travel of this rack in one direction is prevented due to the engagement of the end thereof with the flat bottom of the bore 78, while the travel in the other direction is checked by a heavy compression spring 79 located between the rack 70 and the plug 80 closing the bore 78.

The shell has welded to the extreme end of the external side walls thereof, lugs 81 adapted to receive the free ends of a U-shaped bolt 82 which is secured thereto by nuts 83. This bolt constitutes a handle, and has the side arms thereof

provided with integral collars 84 engaging a cross plate 85, for securing the same to the rear end of the shell. Similarly secured to the front end of the shell, there is a handle 86 and cross plate 87. Secured to the upper end of one of the inner side walls of the shell, there is a rack 88, and to the lower end of the other inner side wall of the shell, there is a similar rack 89 forming with the rack 88 feed engaging means extending substantially the full length of the shell. The end portions of the racks, which are turned cylindrical and threaded, are protruding through the cross plates 85 and 87, to which they are secured by nuts 90. The pinion 55 is capable of operative engagement with either the rack 88 or 15 89, as will be explained hereinafter.

Referring again to the throttle valve 19, it will be seen that the latter is provided with a semi-annular groove 91 in constant communication with the center bore thereof through a radial port 92. From the throttle valve 19, there is a port 93 leading into the annular groove 27 formed around the valve casing 24.

In the operation of the device, assuming that the throttle valve 19 is positioned as shown in Fig. 25 8, and that the valve 33 is positioned as shown in Fig. 3, pressure fluid from the center bore of the throttle valve will flow through the port 92 into the groove 91, from where it will be admitted into the annular groove 27 through the port 93. From 30 the groove 27, the pressure fluid will flow into the valve casing counterbore 26 below the valve flange 35 through the port 28, and thereafter through the ports 37 on the other side of the valve flange 35, thus creating pressure on the large end of 35 the valve for maintaining the same in the position shown in Fig. 3. Simultaneously the pressure fluid from the valve casing counterbore 26, will be admitted into the chamber 71 between the plug 72 and head 70, through the port 40. The 40 pressure thus exerted on the head 70 of the cylindrical rack 68, will drive the latter against the effort of the compression spring 75, imparting thereby rotation to the ring 44 in a counterclockwise direction in Fig. 5. The pawls 49 engage the ratchet tooth 45 of the ring 44, will transmit the rotation of the latter to the element 47, which in turn will transmit rotation to the shaft 53 due to the spline engagement of the former with the latter, thus causing the rotation of the pinion 55 in the same direction as the element 47. The rotation of the element 47 in a counterclockwise direction in Figs. 5 and 6, will cause the pawls 48 to ride over the ratchet teeth 45 of the ring 43, thus permitting the ring 43 to 55 remain stationary. During the slidable movement of the cylindrical rack 68 toward the bottom of the bore 69, the head 70 will uncover the small vent 74, thus creating a drop of pressure between the plug 72 and head 70, and consequently causing 60 also a drop of pressure in the valve casing counterbore 26 through the port 40. The pressure fluid acting on the restricted area of the valve flange 35, will now kick the valve in the position shown in Fig. 4, closing the port 40. In this position of the valve, the pressure fluid remaining in the chamber 71 and port 40, is now free to exhaust to the atmosphere via the ports 41 and 30, groove 29 and ports 31 and 32, permitting thereby a free return of the cylindrical rack 68 in the position shown in Fig. 5. During this return movement of the cylindrical rack 68, rotation in a clockwise direction in Fig. 5 is imparted to the ring 44. During this rotation of the ring 44, the pawls 49 will ride over the ratchet teeth 45 of 70 75

the ring 44, thus permitting the element 47 together with the shaft 53 and pinion 55 to remain stationary. When the valve 33 is positioned as shown in Fig. 4, the pressure fluid is still admitted on the rear face of the flange 36 through the small ports 37. The area of this rear face being larger than the area of the front face of the flange, the pressure fluid acting on the former will again kick the valve into the position shown in Fig. 3, thus closing the communication of the exhaust port 31 with the groove 30, and opening the port 48 for again admitting pressure fluid into the chamber 71 to actuate the cylindrical rack 68 toward the bottom of the bore 69, in the manner previously described.

From the foregoing, it will be understood that an intermittent rotation in only one direction is imparted to the element 47, and consequently to the gear or pinion 55. When it is desired to feed the drilling motor toward the work, the rotating member 61 through its handle 62, is positioned as shown in Fig. 3, thus causing the engagement of the pinion 55 with the rack 88. The rotation imparted to the pinion 55 in a counterclockwise direction in the drawings, will obviously cause the slidable movement of the drilling motor toward the work. The rotating member 61 is maintained in the position shown in Fig. 3 due to the location of the spring pressed plunger 65 within one of the U-shaped grooves 64. When it is desired to reduce the feeding speed of the drilling motor toward the work, the member 61 may be rotated to bring its eccentric finger toward the extreme end of its upward travel relative to the longitudinal center axis of the member 61, thus causing the forcible engagement of the washer 56 with the brake lining 66, for slowing the speed of rotation of the pinion 55, and the speed of feeding motion of the drilling motor 15.

To feed the drilling motor away from the work, the member 61 and its eccentric finger 63 may be rotated about 180°, causing thereby the slidable movement of the washer 56 into the position shown in Fig. 2. In this position of the washer 56, the pinion 55 is now engaging the rack 89, and due to the rotation of the former in a counterclockwise direction, the drilling motor 15 is fed away from the work.

When it is desired to lock the drilling motor against longitudinal movement relative to the support or shell 17, the member 61 may be rotated about 90° from the position shown in Fig. 3, thus positioning the washer 56 about halfway between the extreme ends of its travel within the cap 56, and causing the engagement of the pinion 55 with the racks 88 and 89. The pinion engaging the two racks is held against rotation, thus preventing the longitudinal movement of the drilling motor 15.

The above description is directed to the operation of the feeding mechanism irrespective of the operation of the drilling motor 15. However, when the drilling motor is in operation, that is, when the throttle valve 19 is positioned to afford the communication of the throttle port 22 with the port 23, the reversal of the piston strokes within the motor will impart jars to the motor tending to move the latter relatively to the shell in both directions, and consequently tending to impart oscillatory motion to the pinion 55 and element 47. During the operation of the feeding device, since the pinion 55 is always rotated in a counterclockwise direction, it will be understood that the rotation imparted to the pinion in that last mentioned direction due to the jars of

the drilling motor, will assist the cylindrical rack 68 to feed the drill toward or away from the work. However the rotation of the pinion in a clockwise direction imparted thereto due to the jars of the drilling motor, would tend to move the motor into a direction adversed to the feeding motion imparted thereto by the cylindrical rack 68. Referring to Fig. 6, it will be seen that when the element 47 tends to rotate in a clockwise direction, the pawls 48 engaging the ratchet teeth 45 of the ring 43 will also tend to transmit rotation to the latter, thus causing the slidable movement of the cylindrical rack 77 toward the plug 80. However, the heavy compression spring 79 will prevent the slidable movement of the cylindrical rack 77, thus preventing the longitudinal motion of the drilling motor in a direction adversed to its feeding motion. The compression spring 79 while preventing the slidable movement of the cylindrical rack 77 will compress sufficiently to absorb the shocks resulting from the jars imparted to the drilling motor, reducing thereby the wear and preventing possible breakage of the operative parts.

When the throttle valve 19 is positioned to afford the communication of its port 21 with the port 23, the port 93 is closed by the throttle valve, preventing thereby the operation of the feeding mechanism during the operation of the drilling motor 15. In this instance the drilling motor is fed toward or away from the work, due to the jars imparted to the motor. These jars, as previously explained, will tend to impart oscillatory motion to the pinion 55. Since the latter can only rotate in a counterclockwise direction, the motor will be free to move in one direction relative to the rack with which the pinion is engaged, the direction of movement of the motor being changed by shifting the pinion from one rack to the other.

From the foregoing, it will be understood that the drilling motor may be fed toward or away from the work by the feeding mechanism independently of the operation of the drilling motor, or due to the jars imparted to the latter independently of the operation of the feeding mechanism. It will be further understood that the rate of feeding speed of the motor in at least one direction may be controlled at will, and that the motor may be locked against movement relative to the support.

Although the foregoing description is necessarily of a detailed character, in order to completely set forth the invention, it is to be understood that the specific terminology is not intended to be restrictive or confining, and it is to be further understood that various rearrangements of parts and modification of structural detail may be resorted to without departing from the scope or spirit of the invention as herein claimed.

I claim:

1. In a feeding device for a rock drill, the combination with a support and a drilling motor slidable thereon, a feeding mechanism associated with said motor for imparting forward and backward feeding motion thereto, said mechanism comprising a duality of tooth elements longitudinally of the support, a member carried by said motor capable of operative engagement with the teeth of one or the other of said elements, power actuated means associated with said member for imparting movement thereto relative to said motor, and operable means for selectively moving said member in operative engagement

- with the teeth of one or the other of said elements for causing forward or backward feeding motion of said motor due to the movement of said member relative to said motor.
5. 2. In a feeding device for a rock drill, the combination with a support and a drilling motor slideable thereon, a feeding mechanism associated with said motor for imparting forward and backward feeding motion thereto, said mechanism comprising a duality of racks longitudinally of the support, a gear carried by said motor capable of operative engagement with one or the other of said racks, power actuating means associated with said gear for imparting rotation thereto in a single direction, and operable means for selectively moving said gear in operative engagement with one or the other of said racks for causing the forward or backward feeding motion of said motor due to the rotation of said gear in one direction.
3. In a feeding device for a rock drill, the combination with a support and a drilling motor slideable thereon, an elongated element longitudinally of said support, a member carried by said drilling motor, said element and member having means formed thereon capable of interengagement whereby the rotary motion of said member relative to said element causes the slideable movement of said drilling motor, a mechanism including a gear having a power actuated reciprocable rack associated therewith for imparting rotary motion thereto in alternative direction, and means for transmitting the rotary motion of said gear in one direction to said member irrespective of the rotary motion of the former in the other direction, causing thereby a slideable movement of said drilling motor in one direction.
4. In a feeding device for a rock drill, the combination with a support and a drilling motor slideable thereon, an elongated element longitudinally of said support, a rotatable member carried by said drilling motor, said element and member having means formed thereon capable of interengagement whereby the rotary motion of said member relative to said element causes the slideable movement of said drilling motor, a mechanism associated with said member including a power actuated reciprocable driving element operatively connected with a rotatable driven element for imparting oscillatory motion thereto, and means for transmitting the rotary motion of said driven element in one direction to said rotatory member irrespective of the rotary motion of said driven element in the other direction, causing thereby a step by step slideable movement of said drilling motor.
5. In a feeding device for a rock drill, the combination with a support and a drilling motor slideable thereon, a reciprocatory hammer piston in the motor imparting jars thereto to move the motor in two directions relative to the support, a power actuated mechanism associated with the motor for imparting feeding motion thereto, and cushioned means independent of said mechanism for preventing the movement of said motor in a direction adverse to that of its feeding motion.
6. In a feeding device for a rock drill, the combination with a support and a drilling motor slideable thereon, a reciprocatory hammer piston in the motor imparting jars thereto to move the motor in two directions relative to the support, a rack longitudinally of the support, a gear carried by the motor in operative engagement with said rack, a power actuated mechanism associated with said gear for imparting rotary motion thereto in one direction for feeding the motor longitudinally of the support, and cushioned means independent of said mechanism associated with said gear for preventing the rotary motion thereof in the other direction, preventing thereby the longitudinal movement of the motor in a direction adverse to that of its feeding motion.
7. In a feeding device for a rock drill, the combination with a support and a drilling motor slideable thereon, of a duality of racks longitudinally of said support, a gear carried by said motor capable of operative engagement with one or the other of said racks, a power actuated mechanism associated with said gear imparting rotation thereto in a single direction, said racks and gear arranged and disposed whereby the rotary engagement of said gear with one of said racks causes the feeding motion of said drilling motor in one direction and its rotary engagement with the other of said racks causes the feeding motion of the drilling motor in the other direction, and means for shifting said gear in operative engagement with one or the other of said racks.
8. In a feeding device for a rock drill, the combination with a support and a drilling motor slideable thereon, a reciprocatory hammer piston in the motor imparting jars thereto to move the motor in two directions relative to the support, a duality of racks longitudinally of said support, a gear carried by said motor capable of operative engagement with one or the other of said racks, the jar resulting movement of said motor tending to cause the rotation of said gear in both directions due to its operative engagement with one or the other of said racks, cushioned means for preventing the rotary motion of said gear in one direction permitting thereby the movement of said motor in a single direction during the operative engagement of said gear with one of said racks, and means for shifting said gear from one to the other of said racks, permitting thereby the movement of said motor in the other direction.
9. In a feeding device for a rock drill, the combination with a support and a drilling motor slideable thereon, a reciprocatory hammer piston in the motor imparting jars thereto to move the motor in two directions relative to the support, a movement resisting mechanism associated with said motor for preventing the movement thereof in one direction, said mechanism including a duality of racks longitudinally of the support one higher than the other, and a gear rotatable in a single direction movable axially in operative engagement with one or the other of said racks for controlling the direction of movement of said motor.
10. In a feeding device for a rock drill, the combination with a support and a drilling motor slideable thereon, a reciprocatory hammer piston in the motor imparting jars thereto to move the motor in two directions relative to the support, a movement resisting mechanism associated with said motor, said mechanism including a duality of elements longitudinally of the support, a member carried by the motor for rotation on a stationary axis disposed in equidistant relation with said elements, means on said elements capable of interengagement with similar means on said member for causing the rotation of the latter due to the movement of said motor, stop means associated with said member for preventing the rotation thereof in one direction, and operable means for causing the operative engagement of said

member with one or the other of said elements to control the direction of movement of said motor.

11. In a feeding device for a rock drill, the combination with a support and a drilling motor slideable thereon, a reciprocatory hammer piston in the motor imparting jars thereto to move the motor in two directions relative to the support, a mechanism associated with said motor for controlling the direction of movement thereof, said mechanism including a duality of toothed elements longitudinally of the support, and a member carried by said motor for movement therewith, said member being slideable on an axis perpendicular to said motor for selective engagement with the teeth of one of said elements for preventing the movement of said motor in one direction and with the teeth of the other of said elements for preventing the movement of said motor in the other direction.

12. In a feeding device for a rock drill, the combination with a support formed with side walls having guideways in the upper end therewith, a drilling motor slideable in said guideways, a reciprocatory hammer piston in the motor imparting jars thereto to move the motor in two directions relative to the support, a mechanism associated with said motor for controlling the direction of movement thereof, said mechanism including a rack secured to the upper end of one of the side walls of said support, another rack secured to the lower end of the other of said side walls, a rotatable gear carried by said motor for movement therewith between the side walls of said support, said gear being axially movable in operative engagement with one or the other of said racks, stop means associated with said gear for preventing the rotation of said gear in one direction irrespective of the direction of movement of said motor, and operable means for selectively causing the engagement of said gear with one or the other of said racks, controlling thereby the direction of movement of said motor.

13. In a drilling apparatus, the combination with a support and a drilling motor slideable thereon, a reciprocatory hammer piston in the motor imparting jars thereto to move the motor in two directions relative to the support, and a movement resisting mechanism associated with said motor, said mechanism including a duality of stationary racks disposed in opposition to each other, and a gear carried by said motor movable in engagement with both of said racks for preventing the movement of said motor.

14. In a feeding device for a rock drill, the combination with a support and a drilling motor slideable thereon, a reciprocatory hammer piston in the motor imparting jars thereto to move the motor in two directions relative to the support, a duality of racks longitudinally of the support, a gear rotatably carried by said motor capable of engagement with one or the other of said racks, stop means associated with said gear for preventing the rotation thereof in one direction, and means associated with said gear operable for causing the travel thereof from one to the other of said racks for controlling the direction of movement of said motor, said last means being operable for positioning said gear substantially halfway between the ends of the travel aforesaid, causing thereby the engagement of the gear with both of said racks for locking the motor against movement relative to the support.

15. In a feeding device for a rock drill, the

combination with a support and a drilling motor slideable thereon, a reciprocatory hammer piston in the motor imparting jars thereto to move the motor in two directions relative to the support, a duality of racks longitudinally of the support, a gear rotatably carried by said motor engageable with one or the other of said racks, stop means associated with said gear for preventing the rotation thereof in one direction, said racks and gear arranged and disposed whereby the movement of said motor in one direction is prevented due to the engagement of said gear with one of said racks and in the other direction due to the engagement of said gear with the other of said racks, and means associated with said gear for controlling the rate of speed of said motor in one direction.

16. In a feeding device for a rock drill, the combination with a support and a drilling motor slideable thereon, of a feeding mechanism for said motor comprising a duality of racks longitudinally of said support, a power actuated gear rotatable in a single direction, said racks and gear arranged and disposed whereby the rotary engagement of said gear with one or the other of said racks causes the forward or rearward feeding motion of said motor, means for selectively causing the rotary engagement of said gear with one or the other of said racks, and friction means associated with said gear for controlling the rate of feeding speed of said motor in one direction.

17. In a feeding device for a rock drill, the combination with a support and a drilling motor slideable thereon, a stationary rack, a power actuated gear carried by the motor and meshing with the rack for actuating said motor in one direction, and cushioned means independent of the power actuating said gear for preventing the rotation thereof in the other direction.

18. In a feeding device for a rock drill, the combination with a support and a drilling motor slideable thereon, of a duality of stationary elements, of a power actuated member carried by said motor for movement in a single direction, said member being operatively engageable with one or the other of said elements for feeding said motor in one or the other direction, and means operable for selectively controlling the engagement of said member with one or the other of said elements, controlling thereby the direction of feeding motion of said motor.

19. In a feeding device for a rock drill, the combination with a support and a drilling motor slideable thereon, of a power actuated gear carried by said motor for rotation in a single direction, toothed means on said support with which said gear is engageable for feeding said motor in one or the other direction, and means operable for selectively controlling the direction of feeding motion of said motor irrespective of the rotation of said gear in a single direction.

20. In a feeding device for a rock drill, the combination with a support and a drilling motor slideable thereon, feed engaging means carried by said support, a power actuated element carried by the motor for movement in a single direction engageable with said feed engaging means for transmitting feeding motion to said motor in one or the other direction and means for selectively controlling the engagement of said element with said feed engaging means.

21. In a feeding device for a rock drill, the combination with a support and a drilling motor slideable thereon, a power actuated feeding mechanism associated with said support and motor

- for imparting feeding motion to the latter in one direction, and locking means independent of the power actuating said mechanism for preventing the movement of the motor in the other direction.
- 5 22. In a feeding device for a rock drill, the combination with a support and a drilling motor slideable thereon, of a duality of interengaging elements operatively associated with the support and the motor, a fluid actuated mechanism associated with one of said elements for automatically imparting an intermittent movement there-to relative to the other for effecting a step by step feeding movement in one direction of the motor due to the interengagement of said elements, and locking means independent of the power actuating said mechanism for preventing the movement of the motor in the other direction.
- 10 23. In a feeding mechanism for a rock drill, the combination of a support and a drilling motor slideable thereon, a duality of elements operatively associated with the support and the motor, interengagable means on said elements whereby the rotation of one relative to the other causes the slidable movement of the motor on the support, a ring having one set of internal and one set of external teeth formed thereon, a power actuated reciprocable member operatively associated with one set of said teeth for imparting rotation to said ring, and means operatively associated with the other set of said teeth for transmitting the rotation of said ring to one of said elements for effecting the slidable movement of the motor relative to the support.
- 15 24. In a rock drill, the combination with a support and a motor slideable thereon, of feeding means for said motor including interengageable elements operatively associated with the support and the motor whereby the rotation of one element relative to the other causes the slidable movement of the motor, a mechanism including a rotatable member and a power actuated reciprocable piston operatively associated with said member for imparting rotation thereto, traction means on said member, and means operatively associated with said traction means and one of said elements for transmitting rotation thereto causing the slidable movement of the motor.
- 20 25. In a rock drill, the combination with a support and a motor slideable thereon, of feeding means for said motor including a rotatable and a stationary interengaging element operatively associated with the support and the motor whereby the rotation of the rotatable element relative to the other causes the slidable movement of the motor, a mechanism including a power actuated reciprocable piston operatively associated with said rotatable element for imparting rotation thereto during one stroke of the piston, and means for locking said element against adverse
- 25 26. In a feeding mechanism for a rock drill, the combination with a support and a drilling motor slideable thereon, stationary means carried by the support having a rotatable element active thereupon and carried by the motor for moving the motor relative to the support, a fluid actuated reciprocable member, and means responsive to the reciprocatory movement of said member for effecting the rotation of said element in one direction, said means including a ratchet mechanism having a toothed ring acted upon by said member and pawls engageable with the teeth of said ring for controlling the direction of rotation of said element.
- 30 27. In a rock drill, the combination with a support and a motor slideable thereon, of a feeding mechanism for said motor including a rotatable element carried by the motor, means longitudinal of the support cooperating with said element for effecting the feeding motion of the motor due to the rotation of said element, a power actuated reciprocatory member operatively associated with said element for imparting rotation thereto, and means for selectively controlling the direction of the feeding motion of said motor.
- 35 28. The combination with a support having a drill slideable thereon, of feeding means for the drill comprising a rotatable element carried by the motor, stationary means carried by the support having said element active thereon for feeding the drill relative to the support, means for intermittently rotating said element for effecting a step by step feeding motion of said drill including a motor having relatively movable members one of which is actuated by fluid pressure for reciprocation longitudinally of the support, and means for selectively controlling the direction of feeding motion of the drill.
- 40 29. The combination with a drilling motor having a hammer reciprocable therein, of feeding means for said motor comprising a housing, a fluid actuated piston reciprocable within said housing, means deriving motion from the reciprocation of said piston for transmitting a step by step feeding motion to said motor, and means for selectively controlling the direction of said feeding motion.
- 45 30. The combination with a drilling motor having a hammer reciprocable therein, of feeding means for said drill comprising a housing, a fluid actuated piston reciprocable within said housing, means including an element deriving rotation in one direction from the working stroke of said piston, means for locking said element against rotation in the other direction during the return stroke of said piston, and means responsive to the rotation of said element for effecting a step by step feeding motion of said motor.
